UNITED STATES PATENT OFFICE

148,040

DESIGN FOR A TRACTOR

Edwin S. Steel, Tarzana, Calif., assignor to Bond
Bonham, Claremont, Calif.

Application July 11, 1946, Serial No. 131,509

Term of patent 3½ years

(Cl. D14—3)

To all whom it may concern:

Be it known that I, Edwin S. Steel, a citizen of the United States, residing at Tarzana, in the county of Los Angeles and State of California, have invented a new, original, and ornamental Design for a Tractor, of which the following is a specification, reference being had to the accompanying drawing, forming a part thereof.

Figure 1 is a perspective view of the front and left hand side of a tractor, showing my new design.

Figure 2 is a perspective view of the left hand side of the tractor of Figure 1.

Figure 3 is a perspective view of the right hand side of the tractor of Figure 1.

Figure 4 is a rear elevation of the tractor of Figure 1.

I claim:

The ornamental design for a tractor, substantially as shown.

EDWIN S. STEEL.
